[57] CLAIM

The ornamental design for an inflatable toy vehicle, as shown and described.

DESCRIPTION

FIG. 1 is a top plan view of an inflatable toy vehicle showing my new design;

FIG. 2 is a cross-sectional view thereof taken along line 2—2 of FIG. 1;

FIG. 3 is an end elevational view thereof, the end opposite being a mirror image;

FIG. 4 is a cross-sectional view thereof taken along line 4—4 of FIG. 3;

FIG. 5 is a top plan view of a modified embodiment of the design shown in FIGS. 1 through 4; and

FIG. 6 is a cross-sectional view thereof taken along line 6—6 of FIG. 5.

FIG. 2

FIG. 1

FIG. 5

FIG. 3

FIG. 4

FIG. 6
